UNITED STATES PATENT OFFICE.

JONATHAN TURNER, OF NEW BEDFORD, MASSACHUSETTS.

DESIGN FOR A SCREW-STUD.

SPECIFICATION forming part of Design No. 21,673, dated June 28, 1892.

Application filed January 11, 1892. Serial No. 417,738. Term of patent 14 years.

To all whom it may concern:

Be it known that I, JONATHAN TURNER, a citizen of the United States, residing at New Bedford, in the county of Bristol, State of Massachusetts, have invented and produced a new and original Design for Screw-Studs, of which the following is a specification, reference being had to the accompanying drawing, forming part thereof, the said drawing showing my newly-designed screw-stud in perspective.

The leading feature of the design for a cylindrical screw-stud having an irregular configuration consists of the central contracted portion *c*, the enlarged and similar portions *b d* at the opposite ends of the central portion, and the head *a*, adjacent to the outer end of

the portion *b*, the said head being of greater diameter than the part *b* and provided with screw-threads *a'*. The head *a* is shown as 20 provided with a transverse slot *a²*, and the inner ends of the portions *b d* are beveled, as shown.

I claim—

The design for a screw-stud, as shown and 25 described.

In testimony whereof I have signed my name to this specification in the presence of two subscribing witnesses.

JONATHAN TURNER.

Witnesses:

JAMES W. ALLEN,
JAMES BRENNAND.
